UNITED STATES PATENT OFFICE.

CHARLES J. PEMBROKE, OF ROCHESTER, NEW YORK.

VEHICLE-FRAME.

No. 901,735.

Specification of Letters Patent.

Patented Oct. 20, 1908.

Application filed September 10, 1907. Serial No. 392,109.

To all whom it may concern:

Be it known that I, CHARLES J. PEMBROKE, of Rochester, in the county of Monroe and State of New York, have invented 5 certain new and useful Improvements in Vehicle-Frames; and I do hereby declare the following to be a full, clear, and exact description of the same, reference being had to the accompanying drawings, forming a part 10 of the specification, and to the reference-numerals marked thereon.

The present invention relates to vehicle frames of the type in which a main yieldingly supported frame carries a supplemental frame in a manner to permit the latter to yield independently thereof in order to prevent sudden shocks being transmitted to the occupants of the vehicle, and it has for an object to provide a yielding support which 20 will give a perfectly balanced action, and which may be manipulated from the vehicle without inconvenience.

To these and other ends the invention consists in certain improvements and combinations of parts all as will be hereinafter more fully described, the novel features being pointed out in the claims at the end of the specification.

In the drawings: Figure 1 is a side elevation 30 of a motor vehicle embodying my invention, parts being broken away, and Fig. 2 is a view of the rear end of the vehicle frame.

Similar reference numerals in the several figures indicate similar parts.

35 In the present embodiment of my invention there is employed a main frame 1 yieldingly supported at the front and the rear on axles 2 and 3 by springs 4 and 5 respectively.

The main frame 1 carries a supplemental 40 or seat carrying frame 6 which is guided on the outer side of the main frame by having its side pieces 7 located beyond the side pieces 8 of the latter and is pivoted to the side pieces 8 at its forward end at 9. In this 45 manner the side pieces do not appear conspicuous and are arranged so as to be protected by the seat carrying frame.

Located at the rear of the seat carrying frame is the yielding support of the latter, 50 which comprises an upwardly and rearwardly projecting frame 10 preferably forming part of the main frame and of inverted U-shape and having its arms connected to the side pieces 8 of the main frame. The side 55 pieces 7 of the seat carrying frame are united by a U-shaped piece 11 and the pieces or

frames 10 and 11 are connected by a plurality of vertically arranged parallel coil springs 12, which serve to yieldingly support or suspend the seat carrying frame in a perfectly balanced manner. In order that these springs 12 when broken or otherwise ineffective may be removed for the purpose of replacing them by others, the hooks or eyes 13 and 14 which secure the ends of the springs to the main 60 and to the supplemental frame are open, while for the purpose of adjusting the tension of the springs the hooks 13 are adjustably connected to the frame 10 as by being passed through perforations in the latter and engaged by thumb nuts 15.

It is apparent that by arranging the adjusting devices for the yielding support in an elevated position in the rear of the seat carrying frame, or in other words at the upper 75 ends of the coil springs the occupants of the vehicle may adjust the tension on the springs to suit the road over which they are traveling, without being compelled to leave the vehicle.

Of course the form of the springs, the construction of the adjusting devices therefor and other parts may be changed without departing from the spirit of this invention.

I claim as my invention:

1. In a vehicle frame, the combination with a yieldingly supported main frame, having an upwardly projecting frame at the rear thereof, of a seat carrying frame pivotally mounted at its front end and yieldingly suspended at its rear from the upwardly projecting frame.

2. In a vehicle frame, the combination with a yieldingly supported main frame, of a seat carrying frame pivotally connected at 95 its forward end to the main frame and a plurality of vertically arranged parallel coil springs arranged in rear of and suspending the rear of the seat carrying frame from the main frame.

3. In a vehicle frame, the combination with a main frame having longitudinal side pieces, of a seat carrying frame having longitudinal side pieces pivoted at their forward ends and arranged on the outside and in a horizontal plane with the side pieces of the main frame, and a yielding support for the rear end of the seat carrying frame carried by the main frame.

4. In a vehicle frame, the combination 110 with a main frame having an upwardly extending frame at the rear thereof, of a seat

carrying frame pivotally supported on the main frame, and adjustable yielding devices connecting the upwardly extending frame and the rear end of the seat carrying frame.

5 5. In a vehicle frame, the combination with a main frame having an upwardly extending frame at the rear thereof, of a seat carrying frame pivotally mounted on the main frame, a series of parallel coil springs 10 connecting the upwardly extending frame and the seat carrying frame, and devices for adjusting the tension of the springs arranged at the upper ends of the latter.

6. In a vehicle frame, the combination 15 with a main frame having an upwardly extending inverted U-shaped frame arranged transversely thereof, of a seat carrying frame pivotally supported on the main frame, and a series of parallel coil springs connecting the 20 U-shaped frame and the seat frame.

7. In a vehicle frame, the combination 25 with a main frame having an upwardly ex-

tending inverted U-shaped frame arranged transversely thereof, of a seat carrying frame pivotally supported on the main frame, a series of parallel coil springs connecting the U-shaped frame and the seat frame, and devices for adjusting the tension of the springs, arranged at the upper ends of the springs. 25

8. In a vehicle frame, the combination 30 with a main frame having longitudinal side pieces and an upwardly extending inverted U-shaped frame connecting the side pieces, of a seat carrying frame having longitudinal side pieces pivotally supported on the outer 35 sides of the longitudinal pieces of the main frame, and a series of vertically arranged coil springs supporting the seat carrying frame from the U-shaped frame.

CHARLES J. PEMBROKE.
